(57) **CLAIM**

The ornamental design for handle and trim, as shown and described.

DESCRIPTION

FIG. 1 is a front elevational view of a handle and trim showing my new design, the undisclosed rear is not part of the claimed design; and,

FIG. 2 is a side elevational view thereof, the opposite side is a mirror image.

The dashed lines shown in the figures represent environmental subject matter and form no part of the claimed design.
